UNITED STATES PATENT OFFICE.

SAUL KATZ, OF CHICAGO, ILLINOIS.

CALL BELL OR SIGNALING DEVICE.

Application filed May 24, 1919. Serial No. 299,558.

To all whom it may concern:

Be it known that I, SAUL KATZ, a citizen of the United States, residing in Chicago, in the county of Cook and State of Illinois, 5 have invented certain new and useful Improvements in Call Bells or Signaling Devices, of which the following is a specification.

This invention relates to that class of signaling devices having a pair of electromagnets adapted to be connected with a single battery or source of electric supply and with three different electrical circuits in such a manner as to enable a different signal to be 15 given by the closing of each circuit, respectively.

The principal object of the invention is to provide a simple, economical and efficient electrically actuated signaling device.

20 A further object of the invention is to provide an electrically actuated signaling device in which two movable signaling members, such as a bell hammer and a buzzer may be actuated in such a manner as to enable 25 three different and distinct signals to be given thereby, by means of a pair of electromagnets, a single battery or source of electrical supply and three circuits each adapted to be closed by a switch, in any desired 30 order.

Other and further objects of the invention will appear from the following description and claim, and from an inspection of the accompanying drawings, which are made a 35 part hereof.

The invention consists in the features, combinations, and construction and arrangement of parts herein described and claimed.

In the accompanying drawings—

40 Figure 1 is a view in front elevation of a signaling device constructed in accordance with my invention;

Fig. 2 is a view in side elevation of the same; and

45 Fig. 3 is a diagrammatic view indicating the circuits, and the arrangement of the cores and coils or windings of the electromagnets, and their connections, as well as the armatures, circuit-breakers or interrupters, and 50 switches.

In constructing an improved signaling device in accordance with my invention, I provide a metallic base plate 1, which is adapted to be mounted upon a suitable support, 55 and is provided with a standard 2 fixed to said base plate and forming a support for a

bell 3 which is secured in position upon the standard by means of a screw 4, or similar securing means.

Four binding posts 5, 6, 7, and 8 are 60 mounted upon the base plate, the posts 5, 6 and 8 being insulated from the base plate by means of suitable insulating material 9, 9, 9, in the ordinary manner, and the post 7 being in metallic contact or connected with 65 the base plate by electrically conductive means in any ordinary and well known manner.

Two electromagnets are provided, one having a metallic core 10 around which is wound 70 a coil 11 of insulated wire; and the other having a metallic core 12 around which is wound a similar helical coil 13 of insulated wire. It will be noted that these coils are not directly connected, but that each is separately wound upon its core of soft iron or other suitable material, each core being provided at its opposite extremities with disks or washers 14 through which the ends of the core project. Each core with its insulating 80 end washers or disks 14, 14, thus forms a spool upon which its coil is wound between said end disks.

A very simple and efficient means for supporting the electromagnets in position upon 85 the base plate in parallel relation and spaced apart so that they are quite separate and not directly connected, consists of a flat sheet metal plate 15 laid flat upon the face of the base plate 1, and secured to the latter by 90 means of screws 15' or other suitable securing means.

The main body of the sheet metal plate 15 has a side flange 16 at or near its upper extremity bent into perpendicular relation to 95 the main body of the plate and located endwise beyond the corresponding end of the core 10 or upper magnet comprising core 10 and coil 11. On the same side of the plate 15 is another relatively long flange 19 which 100 is perpendicular to the main body of the plate and parallel with respect to the flange 16, and on the opposite side,—and at or near the lower extremity of the plate 15 from the flanges 16 and 19,—is a side flange 20, 105 which is located beyond the end of the core of the lower electromagnet.

To the flange 16 is secured the upper flexible end of an armature 17 which has a spring contact or interrupter 18 mounted 110 on the outside thereof in position to be normally in yielding engagement with an in-

sulated metallic contact post 21 mounted upon a layer or plate of insulating material 22 which is secured to the main base plate 1 by means of securing hooks 23 or other suitable securing means. This armature 17 serves as a buzzer armature.

The upper and lower electromagnet are supported by the vertical flange 19 which is located between the ends of the electromagnets and the armature 17 and provided with suitable apertures through which the adjacent ends of the cores 10 and 12 extend—the lower core 12 being in position to actuate the buzzer armature 17 when said core is energized.

A bell-hammer armature 24 has its flexible bottom end attached to the bottom side flange 20 by means of a rivet 20' or other suitable ordinary securing means, and is provided with a bell hammer 25 fixed to the upper end of said armature, in position to swing into and out of striking contact with the bell 3 as the armature is actuated. A spring contact member or interrupter 26 is attached to the bell armature 24 in position to normally yieldingly engage a contact post 27 which is of metal and mounted upon a layer or plate 28 of insulating material attached to the base plate 1 by means of securing hooks 29, or other suitable securing means.

The spring contact or interrupter 26 is of spring metal or resilient material and projects downward beyond the lower extremity of the relatively heavy body portion of the armature 24 and is attached to and in contact with the flange 20 already described, so that the bottom extremity of the armature is thus resilient or flexibly connected with the supporting flange.

The spring contact or interrupter 26 on the buzzer armature 17 is, by preference, of lighter construction or more flexible than the spring contact member or interrupter 26 on the bell-hammer armature 24, and the armature 24, with its bell hammer thereon, is heavier and less easily vibrated than the buzzer armature 17. In other words, the buzzer armature and bell-hammer armature are so constructed and arranged that less force or energy is required to operate the buzzer armature than is required to actuate the bell hammer armature.

It is important that the disadvantages which result from a construction and mode of operation whereby the buzzer armature is actuated during the operation of the bell hammer armature, as in the case of certain known devices, should be avoided. It is particularly desirable that the confusion of sounds or signals, and the needless waste of energy which results from actuating the buzzer armature during the operation of the bell-hammer armature, as in the case of de-

hammers required to produce a louder noise than is at the same time produced by the buzzer armature operating at the same time with the bell, should be avoided, as it is in my improved device herein described and shown.

The circuits are as follows: It should be noted that the coils or windings 11 and 13 are not directly connected, but are separate, and are spaced apart, as shown.

The battery D, or source of electric supply, serves to supply all of the circuits, of which there are three. And there is a circuit closer in the form of a switch or push button in and for each circuit.

The insulated binding post 5 is connected with the battery D by means of wires 30 and 31 which are connected with a circuit closer in the form of a switch or push button A, for actuating the bell-hammer armature to cause the bell to be struck once for each operation of the switch. The insulated binding post 6 is connected with the opposite terminal of the battery by means of a battery wire 32.

The binding post 7, which is not insulated, but is in contact with the base plate 1, is connected with the battery by means of battery wires 33, 34, and 31, the wires 33 and 34 being connected with the circuit closer, switch or push button B, for actuating the bell hammer armature 24 when a continuous series of strokes in quick succession is to be obtained by operating the circuit closer B once for such vibrating action or continuous series of successive strokes of the bell hammer.

The insulated binding post 8 is connected with the battery by means of battery wires 35 and 36, and wires 34 and 31, the wires 35 and 36 being connected with circuit closer, switch or push button C, for actuating the buzzer armature, which is accomplished without actuating the bell hammer armature.

The insulated binding post 5 is connected by wire 37 with the insulated post 27, and thence, by wire 38 to the coil or winding 11 of the upper electromagnet, and thence by wire 39 to the insulated binding post 6, which is connected with the battery by wire 32, as already described. Therefore, when the circuit closer or push button A is pressed or closed, the circuit is closed from battery D through wire 31, circuit closer A, wire 30, insulated post 5, wire 37, coil 11 (the upper coil), wire 39, insulated post 6 and wire 32 to the battery, thus energizing the core 10 of the upper electromagnet, thereby actuating the bell-hammer armature 24 so as to cause the bell hammer to strike the bell a single stroke, and without actuating the buzzer armature.

When the circuit closer or push button B

- is closed, the circuit is closed from battery D through battery wire 32, insulated post 6, wire 39, upper coil or winding 11, wire 38, insulated post 27, spring contact or interrupter 26, armature 24, supporting flange 20, base plate 1, to non-insulated post 7, which is grounded, thence through battery wire 33, circuit-closer B, wire 34 and wire 31, to the battery, thereby causing the core 10 of the upper electromagnet to be energized, so as to actuate the bell hammer armature 24 and interrupter 26, and produce a continuous series of strokes of the bell, or what may be termed a vibratory action 15 of the bell hammer, without energizing the core 12 of the lower electromagnet, and therefore, without actuating the buzzer armature 17 during the operation of the bell hammer armature.
- 20 When the circuit closer or push button C is closed, the circuit is closed from battery D through wire 32, post 6, wire 39, upper coil 11, wire 38, insulated post 27, spring contact 26, bell hammer armature 24, armature-supporting flange 20 to the base plate 1, thence through grounded armature 17, or "buzzer," interrupter or spring contact 18, post 21, and wire 40, to the lower coil 13, thence through wire 41 through the insulated binding post 8, wire 35, circuit closer C, wire 36, wire 34 and wire 31, to the battery D, thereby causing the cores of both the upper and lower electromagnets to be energized, and, by causing the current to pass through the coils of both of said electromagnets, providing additional resistance to the current, so that, although there is sufficient energy provided to actuate the buzzer armature by energizing the core 12 35 of the lower electromagnet—the buzzer armature being lighter and more easily operated than the bell hammer armature—the bell hammer armature will not be actuated during the operation of the buzzer.
- 40 From the foregoing it is obvious that the buzzer armature will not be actuated during the operation of the bell hammer armature, for the reason that the circuit is through the coil of the upper electromagnet, so as to energize the core of the upper magnet, but not through the coil of the lower magnet when the bell hammer armature is actuated either for a single stroke or for a continuous series of strokes in rapid succession.
- 45 It follows that the buzzer armature is not actuated during the operation of the bell hammer armature so as to cause a confusion of noises or signals, which would be very undesirable and objectionable for many reasons, as will be readily understood and appreciated by those skilled in the art.
- 50 From the foregoing it is plain that a combined bell and buzzer are mounted on one base, and constructed to enable three distinctly different signals to be given sepa-
- rately and in any desired order, each by the closing of a distinct and separate switch, each of such switches being adapted to be operated in the same manner—for instance, by the pressing of a single push button, all of 70 the push buttons or switches having no only the same mode of operation, but the simplest and most convenient mode of operation, and not requiring the operation of more than one switch for any given circuit, or the operation of a switch to different positions. And the device, having these advantages and capable of accomplishing these purposes in an efficient manner is so constructed as to eliminate the use of unnecessary wiring and parts, and also eliminates the objectionable feature of having the buzzer operate when the bell hammer is operated to cause a series of successive strokes, as distinguished from 75 a single stroke of the bell, to be made.
- 80 In order to provide a device having all of the above mentioned advantages, and which is capable of accomplishing all of the above mentioned objects, all of which are not accomplished by any device known to the art, 85 I find it advantageous and desirable to provide means, preferably in the form herein described and shown, for connecting coils 11 and 13 in series when it is desired to operate the device as a buzzer, as any device which 90 would operate by merely closing a circuit containing the coil 13, would interfere with the operation of one or both of the other two circuits, or else would render it necessary to change the wiring of one or both of the other 95 two circuits, or add unnecessarily to the wiring and parts or change the mode of operation of the parts to the detriment of the device.
- 100 It is very desirable to use the metallic base plate which supports the coils and electrically operated parts of the device, as an electrical conductor which coacts with the wiring of a plurality of the three circuits, preferably the circuit for operating the 105 buzzer and the circuit for operating the bell hammer to produce a series of successive strokes, and without rendering it necessary to cause the buzzer to operate simultaneously with or during the ringing of the bell, 110 and in order to accomplish this, as well as the other advantages and desirable objects above mentioned, I find it advantageous, and I believe it to be necessary, to provide means 115 for connecting the coils 11 and 13 in series instead of merely closing a circuit containing the coil 13 only, or unnecessarily increasing the wiring, or complicating the connections between the battery and the coils, or between the battery and the electrical conductors of one or more of the three circuits.
- 120 I claim:
- 125 In a signaling device, the combination of a metallic base, a bell, a bell hammer, a bell hammer armature, a buzzer armature, a pair 130

of separate electro-magnetic coils, a core encircled by one of said coils only and having an end of said core adjacent to the bell hammer armature, and acting to actuate said armature without actuating the buzzer armature when the said coil and core are energized, a second core encircled by the other one of said separate coils and having an end of said last mentioned core adjacent to the buzzer armature, and acting to actuate the same when said core is energized, three circuits each adapted to be connected with a source of electric supply, a circuit closer in each of said circuits, one of said circuits passing through one of said coils and acting to energize one of said cores only, namely the first mentioned core, for actuating the bell hammer to produce a single stroke of the bell hammer, another of said circuits pass-

ing through said last mentioned coil and 20 through an interrupter connected with the bell hammer armature, and acting to energize said core only, for producing a continuous series of successive strokes of the bell hammer armature without actuating the 25 buzzer armature, and a third circuit passing through both of said coils and through an interrupter on the buzzer armature and acting to actuate the buzzer armature only, said buzzer armature and its interrupter being 30 lighter and more easily operated than the bell hammer armature and its interrupter.

Signed at Chicago, Illinois, May 20, 1919.

SAUL KATZ.
